UNITED STATES PATENT OFFICE.

JOHN W. GRAY, OF SALT LAKE CITY, UTAH.

STIFFENING-CAPE FOR COAT-COLLARS.

No. 882,674.

Specification of Letters Patent. Patented March 24, 1908.

Application filed October 16, 1907. Serial No. 397,713.

To all whom it may concern:

Be it known that I, JOHN WILLIAM GRAY, a citizen of the United States, residing at Salt Lake City, in the county of Salt Lake 5 and State of Utah, have invented certain new and useful Improvements in Stiffening Capes for Coat-Collars; and I do hereby declare the following to be a full, clear, and exact description of the invention, such as 10 will enable others skilled in the art to which it appertains to make and use the same.

My invention relates to stiffening capes for coat collars (this invention being an improvement on my former application Serial 15 No. 386,401, filed July 31, 1907), and the object of my invention is to produce a device which shall prevent the wrinkling or sinking in of the body of the coat immediately below the collar where it lies over the back of the 20 neck of the wearer.

As is well known with persons having long necks or even when their necks are short, the collar of the coat sooner or later falls back from the collar of the shirt and a wrinkle 25 forms in the body of the coat just below the collar and just back of the neck of the wearer and about midway between his shoulders, thereby producing an unsightly and ugly appearance. In order to prevent this, it is 30 generally necessary to have a coat fitted by a skilled tailor and even then if the coat is not lined or the tailor is not skilful, the collar of the coat will sooner or later fall away from the collar of the shirt and the coat present 35 the appearance of having been cheaply made.

More specifically stated, it is the object of my invention to prevent these defects, and to these ends my invention consists in a stiffening cape substantially of the form shown 40 in Figure 3, and which is inserted underneath the body of the coat at the back of the neck, as shown in Figs. 1 and 2, and which serves to hold the collar of the coat yielding 45 against the collar of the shirt, thereby preventing all wrinkling and causing the coat to have the appearance of having been made by a skilful tailor.

Referring to the accompanying drawings forming a part of this specification:—Fig. 50 1 represents a coat as worn by the wearer and having my improvement applied thereto, the said improvement being shown in dotted lines. Fig. 2 is a vertical sectional view taken through the collar of a shirt, the collar 55 of a coat, and my improved stiffening cape. Fig. 3 is a plan view of my invention de-

tached from the coat with parts of the same broken away. Fig. 4 is an end view of my improved cape, when detached from the coat, and Fig. 5 is a sectional view of a part of the 60 cape on an enlarged scale, showing the structure of the hair cloth used therein.

My invention as described in my former application above referred to, has proved very effective and useful, but I have discovered that by putting an additional narrow band of hair cloth with the fibers running in one direction only, and at right angles to the main hair cloth, a still further improved effect is obtained, as vertical wrinkling is thereby more effectually prevented. 65

A represents the back of the coat, B the outer fold of the coat collar, and C the inner edge of the same where it is stitched to the body of the coat. This inner edge C of the 70 coat collar is preferably divided as shown in Fig. 2, and the part D separated from the part C, and the inner lining of the coat, if there be one, is secured to the same. 75

Into the space formed by separating the 80 parts C and D, I insert my improved stiffening cape and stitch the parts C and D to the lining H of the coat securely thereto. This stiffening cape is composed of an outer layer E of suitable material, a central layer F, 85 preferably of hair cloth, and an inner layer G of any suitable material, preferably canvas, all of these parts being securely fastened together. This is the construction described in my former application, but I have discovered that by putting an additional layer of hair cloth K, in the form of a narrow strip running longitudinally of the cape, near its lower edge, the four parts then being securely 90 stitched together, an additional function is 95 secured, namely, the prevention of vertical wrinkles.

The cape occupies the position shown in Figs. 1 and 2, and preferably extending three or four inches below the lower edge of the 100 coat collar, and along all its edges is securely stitched to the coat. The layer F, of hair cloth or other resilient material, with which my cape is provided, causes the same to have considerable flexibility in the direction of its length, and yet exerts such a sustaining action upon the collar of the coat as to hold it snugly against the collar J of the shirt L, and thereby secure a neat appearance at all times. By actual experience I have found 105 that it is possible to take ready made coats, insert stiffening capes therein, of the form 110

described and in the manner shown, and that the result is that the appearance of said coats, under all conditions of wear and at all times, is better than if they were made by a 5 skilled tailor. The hair cloth used in the layer F of my stiffening cape has the hairs running only in one direction, namely, vertical, the other threads of cloth running at right angles thereto and being made of linen 10 or fibrous material. The strip F, of hair cloth, is so arranged that the hairs run perpendicularly, thus preventing horizontal wrinkling while allowing the cape to bend easily around the neck. This results in a 15 more resilient action of the cloth and renders it more difficult to detect the cape underneath the coat.

Vertical wrinkling sometimes occurs in coats, especially if they are made of thin material, and for this reason I use the narrow 20 strip of hair cloth K. As shown in Fig. 3, this is much narrower than the strip of hair cloth F, as I have found by experience that a very narrow strip is sufficient to prevent vertical wrinkling, and I do not desire to make the cape too thick.

In the enlarged section shown in Fig. 5, M represents the hairs in the hair cloth strip K running longitudinally, and N represents 30 the hairs in the hair cloth F running vertically.

It will be seen that my invention is very simple in construction, easy to apply to a coat whether during the making thereof or 35 after the same is made, and that it is cheap. By actual test I have found it to be most efficient, and I have also found that it will keep the collar of a coat appearing neat and tailor-made as long as the coat will last.

40 The cape is preferably made in the shape approximately shown in Fig. 3. Of course, capes of various size are used with different coats.

I claim:—

45 1. A coat provided with a stiffening cape under its collar and inside the lining at the back thereof, said cape composed of a plurality of layers of material, one of which is hair cloth having its hairs running up and down the back of the coat and thereby preventing the coat from wrinkling under the collar when in use, substantially as described.

50 2. A coat provided with a stiffening cape

under its collar and inside the lining at the 55 back thereof, said cape composed of an outer layer of fabric, a middle layer of hair cloth, having all its hairs running up and down the back of the coat, and an inner layer of canvas, and said cape serving to prevent 60 the coat from wrinkling under its collar when in use, substantially as described.

3. A stiffening cape for coat collars shaped to fit the coat under the collar at the back thereof and comprising an outer layer of 65 fabric, a middle layer of hair cloth having all its hairs running in the direction of the shortest dimensions of the cape, and an inner layer of canvas, substantially as described. 70

4. A coat provided with a stiffening cape under its collar, said cape being composed of a plurality of layers of material, one of which is hair cloth having its hairs running up and down the back of the coat, and another of 75 which is a longitudinally disposed strip of hair cloth having the hairs running at right angles to those of the first named layer, thereby preventing wrinkling of the coat under the collar when in use, substantially as 80 described.

5. A coat provided with a stiffening cape under its collar, and inside the lining at the back thereof, said cape being composed of an outer layer of fabric, a middle layer of hair 85 cloth, having its hairs running up and down the back of the coat, an inner layer of canvas, and a narrow horizontal strip of hair cloth in the inside of the cape, near its lower edge, having all the hairs thereof running 90 horizontally, substantially as described.

6. A stiffening cape for coat collars, adapted to fit the coat under the collar at the back thereof, and comprising an outer layer of fabric, a middle layer of hair cloth, having 95 all its hairs running in the direction of the shortest diameter of the cape, an inner layer of canvas and a narrow strip of hair cloth, near the bottom of said cape, having all its hairs running longitudinally, substantially 100 as described.

In testimony whereof, I affix my signature, in presence of two witnesses.

JOHN W. GRAY.
